UNITED STATES PATENT OFFICE.

J. W. LIVINGSTON AND S. A. LIVINGSTON, OF HARTFORD, CONNECTICUT.

IMPROVEMENT IN SASH SUPPORTER AND FASTENER.

Specification forming part of Letters Patent No. **58,655**, dated October 9, 1866.

To all whom it may concern:

Be it known that we, J. W. LIVINGSTON and S. A. LIVINGSTON, of the city and county of Hartford, and State of Connecticut, have invented a new and Improved Sash-Supporter; and we do hereby declare that the following is a full, clear, and exact description thereof, which will enable others skilled in the art to make and use the same, reference being had to the accompanying drawings, forming part of this specification.

The present invention relates to a simple, cheap, and efficient attachment to the sash-frame of a window, to act as a support or fastener thereto when it is raised or lowered, as will be obvious from the following detail description thereof, reference being had to the accompanying plate of drawings, in which—

Figure 1 is a view of one side of the sash-frame, with it broken out to show the manner of arranging our improved supporter therein; Fig. 2, a transverse section taken in the plane of the line *x x*, Fig. 1; Figs. 3 and 4, detail views.

Similar letters of reference indicate like parts.

A in the drawings represents one side of a sash-frame, which is to be suitably cut out upon its edge in contact with the window-frame to receive the sash-supporter *B*, which is made and arranged as follows: *C*, a frame or plate made of cast or malleable iron or any other suitable metal or material; *D*, a friction-roller having a rubber band, *E*, placed around its periphery; *F*, a spring made of metal and punched out of a sheet in the form plainly shown in Fig. 4 of the drawings—that is, with two arms, *G G*.

The roller *D* is hung in bearings upon the back or rear side of the frame or plate *C*, with its periphery projecting through an opening, *H*, in the said plate, this roller being held in and to its bearings upon the plate by means of the two arms *G G* of the spring *F*, that is secured to the plate *A* in proper position

therefor when the plate is secured in and to the edge of the sash, so as to be flush, or nearly so, therewith.

From the above description of the arrangement of the friction-roller *D* in the sash-frame it is plainly obvious that if the sash-frame is either raised or lowered it will be held in any desired position or height by the said friction-roller *D*, which, by its arrangement, thus operates as a support therefor, and that, furthermore, if a cavity or depression be formed in the lower portion of the window-frame in proper position to receive the friction-roller, when the sash is closed down upon the window-sill, by the use of a pin, *K*, inserted in the sash and in proper position, that, when pushed in, it will come to a bearing against the periphery or edge of the said roller and prevent it from moving inward, a perfect fastening of the sash is secured, as by means of such pin, when so brought to bear against the friction-roller, it is rendered impossible for the roller to move out of the cavity of the window-frame until such pin has been relieved therefrom.

We claim as new and desire to secure by Letters Patent—

1. The friction-roller *D* and spring *F*, when combined and arranged substantially as and for the purpose specified.

2. In combination with the foregoing, the use of a pin, *K*, or its equivalent, as and for the purpose described.

The above specification of our invention signed by us the 4th and — days of April, 1866, respectively.

S. A. LIVINGSTON.
JOSEPH W. LIVINGSTON.
